L. G. SIMPSON.
LENS GRINDING MACHINE.
APPLICATION FILED FEB. 1, 1919.

1,381,246.

Patented June 14, 1921.

UNITED STATES PATENT OFFICE.

LEON G. SIMPSON, OF ROCHESTER, NEW YORK, ASSIGNOR TO BAUSCH & LOMB OPTICAL COMPANY, OF ROCHESTER, NEW YORK, A CORPORATION OF NEW YORK.

LENS-GRINDING MACHINE.

1,381,246.

Specification of Letters Patent. Patented June 14, 1921.

Application filed February 1, 1919. Serial No. 274,515.

To all whom it may concern:

Be it known that I, LEON G. SIMPSON, a citizen of the United States, residing at Rochester, in the county of Monroe, State of New York, have invented certain new and useful Improvements in Lens-Grinding Machines; and I do hereby declare the following to be a full, clear, and exact description of the same, reference being had to the accompanying drawings, forming a part of this specification, and to the reference-numerals marked thereon.

One object of my invention is to embody in a single integral unit that part of a lens grinding machine comprising a grinding lap spindle and its driving and control mechanism. Another object of my invention is to provide a simple, compact and inexpensive frame for lens grinding machines in which suitable bearings are provided for both the driving shaft and the shaft for the grinding lap or shell. Still another object of my invention is to provide a simple bearing support for the driving shaft of a lens grinding machine by which several machines can be conveniently connected to be driven in unison.

In the drawings:

Figure 1 is a perspective view of a lens grinding machine unit constructed in accordance with my invention.

Fig. 2 is a front elevation of a pair of lens grinding machines involving two of the lens grinding machine units illustrated in Fig. 1 coupled together to provide a gang of lens grinding machines adapted for individual or simultaneous operation.

My prescription lens grinding machine comprises an abrading or grinding mechanism, driving mechanism therefor and mechanism for controlling the speed of and stopping the grinding mechanism. I have provided a single frame, indicated generally by 1, in which these devices are mounted. The frame 1 is secured to the under side of a work bench or table 2 by any suitable means, preferably by bolts passing through the flange 3 into the table. A horizontally disposed driving or countershaft 4 is journaled in a pair of alined bearing bosses 5 and 6 which are formed respectively on the extremities of the arms 1^a and 1^b of the frame 1. A driving pulley 6^a is fixed to one end of the shaft adjacent the bearing boss 5,

and a thrust collar 7 fixed to the shaft adjacent the opposite side of said boss, prevents longitudinal movement of the shaft. A driving wheel 8 is mounted on the countershaft to rotate therewith but also to have axial movement thereon, by means of a feather 10 engaging a groove 11 in the shaft. A spindle 12 having an abrading shell or lap 13 is mounted at substantially right angles to the shaft 4 in a pair of alined journals 14 and 15. The journal 14 is formed on the arm 16 provided therefor on the frame arm 1^a and the journal 15 is formed integral with the flange 3 by which the frame 1 is secured to the table 2 and extends upwardly through the table. Keyed or otherwise secured to the spindle 12, is a face friction wheel 18, the under face of which is adapted to engage the periphery of the driving wheel 8. In order to make the frictional engagement of the wheel 18 with the periphery of the wheel 8 more positive, the wheel 8 may be provided with a frictional surface 9 of felt, leather or the like. Coöoperating with the abrading shell or lap 13 is a carrier 19 for a lens blank supported on a lever 20 pivotally supported in the upper end of a post 21 mounted on a bracket 22 supported on the table 2.

Means are provided for moving the wheel 8 along the shaft 4 radially of the wheel 18 to vary the speed at which the shaft 12 is driven. To this end, the hub 23 of the wheel 8 is provided with a circumferential groove or slot 24 with which coöperates a yoke or fork 25 pivoted to the end of the link 26, 90 which in turn is pivoted to the end of an arm 27, having a hub 28 secured to the end of a shaft or spindle 28^a. To the upper end of the shaft 28, which is supported by its bearing in a boss 29 that is provided therefor on the arm 1^b of the frame 1, and that extends upwardly through the table 2, is secured the crank or arm 30 having the knob 31 whereby the shaft 28^a and its associated mechanism is manually manipulated. The construction is such that the movement of the crank 30 moves the driving wheel 8 along its shaft 4 radially of the driven face wheel 18, in order that said driven wheel will be rotated at a higher speed when engaged near its center by the driving wheel 8 and at a lower speed when engaged near its periphery by said driving wheel.

In order to stop the rotation of the grinding shell 13 instantly at will, I provide a 5 brake member 32 mounted on a bent arm 33 secured to the hub 28 of the lever 27. The 10 brake member 32 comprises an L shaped plate member 34 pivoted or hinged at 35 to a plate 36 secured to the arm 33. Mounted on the working face of the member 34 is a friction member 37 which may be of fibrous material such as leather, felt or the like.

When the crank 30 is manipulated to bring the driving wheel 8 to the periphery of the driven wheel 18 and the brake member 32 is brought into engagement therewith as shown in the left of Fig. 2: the working face 34 of the brake member which normally assumes a slightly inclined position as shown in Fig. 1, passes under the outer edge of the wheel 18 and wedges it, together with the spindle 12 and parts carried thereby, out of contact with the driving wheel 8; the member 32 simultaneously assuming a substantially horizontal position as the heel of the member 34 is brought into contact with the periphery of the wheel 18. During the process of disengaging the driven wheel 18 from the driving wheel 8, the friction between the brake member 32 and the wheel 18 quickly checks the rotation thereof together with its associated parts and brings it to a stop.

It will be noted that the frame 1 is simple and strong in design and that it affords bearings for the countershaft and for the grinding spindle 12 at substantially right angles to each other, and also a bearing support for the devices which control the speed of and stop the grinding shell. When it is desired, as frequently happens, to set up a plurality of machines in gangs or series as shown in the drawings, they are secured to the bench 2 with the ends of their countershafts 4 in alinement. The pulleys 6^a are removed from all but the first machine and the ends of the shafts connected by means of an Oldham coupling 40 as shown.

Having described my invention, what I

claim and desire to secure by Letters Patent is:

1. A supporting frame and power transmission device for a grinding machine comprising a flange at the top thereof for supporting the entire frame, a pair of oppositely disposed arms inclined outwardly and downwardly from said supporting flange, horizontal bearing bosses in the ends of said arms, a driving shaft journaled in said bearing bosses, a driving wheel fixed to said shaft between said bearing bosses, a vertical bearing boss supported from one of said arms above the horizontal shaft, a vertical shaft above said horizontal shaft journaled in the supporting flange and the vertical bearing boss, a driven wheel fixed to said vertical shaft between said flange and vertical bearing boss and adapted to coöperate with said driving wheel, one of said wheels being slidably fixed to its shaft, and means supported by one of said arms for adjusting said slideable wheel to vary the speed of the vertical shaft.

2. A supporting frame and power transmission mechanism for a grinding machine comprising in combination a supporting flange at the top of the frame adapted to be attached beneath a table, arms inclined outwardly and downwardly from said flange, horizontal bearing bosses in the lower ends of said arms, a driving shaft journaled in said bearing bosses, a driving wheel fixed on said shaft between the latter, a vertical bearing boss above said shaft, a projection on one of said arms supporting said vertical bearing boss, a vertical shaft journaled in said flange and said vertical bearing boss, a driven wheel fixed on said vertical shaft between the flange and vertical bearing boss and adapted to coöperate with the driving wheel, one of said wheels being slideable on its shaft, and a coupling device on said driving shaft outside of the horizontal bearing boss but adjacent thereto whereby a plurality of individual frames may be alined adjacent each other.

LEON G. SIMPSON.
